UNITED STATES PATENT OFFICE.

PHILIP N. BRAUN, OF SYRACUSE, NEW YORK, ASSIGNOR TO THE PROSPERITY CO. INC., OF SYRACUSE, NEW YORK, A CORPORATION OF NEW YORK.

SHIRT-IRONING MACHINE.

Application filed July 23, 1920. Serial No. 398,508.

To all whom it may concern:

Be it known that I, PHILIP N. BRAUN, a citizen of the United States, and a resident of Syracuse, in the county of Onondaga and 5 State of New York, have invented a certain new and useful Shirt-Ironing Machine, of which the following is a specification.

This invention relates to shirt ironing machines and has for its object a particularly simple and efficient collar band holder, which is a self-contained structure and readily applied to a pressing machine; and further which is particularly applicable to pressing machines having an upper pivoted 10 pressing head of the type shown in Patent No. 1,252,988, issued Jan. 8th, 1918 whereby such machines can be used as shirt ironing machines.

The invention consists in the novel features and in the combinations and constructions hereinafter set forth and claimed.

In describing this invention, reference is had to the accompanying drawings, in which like characters designate corresponding parts in all the views.

Figure 1 is a side elevation of a pressing machine embodying my invention.

Figure 2 is a fragmentary face view of the upper pressing head.

Figure 3 is a fragmentary face view of the lower bed or buck.

Figure 4 is an enlarged plan view of the collar band holder, the contiguous portion of the lower buck being also shown.

Figure 5 is a sectional view on line 5—5, Figure 4.

Figure 6 is a detail view of a detached clamping member.

This shirt ironing machine comprises generally a lower pressing bed or buck, an upper pressing head movable toward and from the buck and carried by a support in the form of a lever pivoted between its ends to the frame of the machine and carrying the pressing head at its front end, the pressing head having an arcuate cutout at one end, and a collar band holding means mounted on the face of the lower buck and including operating members extending upwardly through the cutout when the pressing head is down, this collar band holding means being preferably a self-contained structure detachably mountable on the lower buck.

1 designates the lower bed or buck, and 2

the upper pressing head, the lower buck being mounted upon a frame or table 3, and the pressing head being carried at the front end of a support as a lever 4 pivoted at 5 between its ends on a horizontal axis to a standard 6 forming part of the frame and being connected at its rear end to operating mechanism including toggle links 7 and 8 and a treadle 9. Also a suitable counterbalancing weight 10 is mounted on the rear end of the lever. The upper and lower bucks 1 and 2 are suitably heated by steam or other heating medium conducted through the hollow interiors thereof.

The upper pressing head 2 is formed with an arcuate cutout 11 at one end and collar band holding means is mounted on the upper face of the lower buck in alinement with its cutout.

12 designates the collar band holding unit. The collar band holding means or unit 12 comprises a base 13 mounted on the lower buck 1 and having an upwardly extending part and clamping means supported by said part coacting with the base to hold the collar band, said means projecting through the arcuate cutout 11 of the pressing head 2 when the pressing head is down.

The base 13 is here shown as provided with a stem 13^a which extends through a hole 14 in the lower buck and which is threaded at its lower end to receive a nut 15. Also the base is formed with a depending boss 16 from which the stem projects, the boss 16 being arranged in the recess or countersink 1^a in the lower buck. This boss 16 is formed with a guideway for the purpose hereinafter described. The base 13 is here shown as provided with an upwardly extending arm 18 and with an arcuate beveled edge face 19.

The clamping means cooperate with the base to hold the collar band, is carried by the arm 18 and movable vertically along the same, and includes a member movable toward and from an arcuate edge face 19 of the base to clamp a collar band against the same.

In the illustrated form of my invention, this means comprises a carriage or slide 20 movable in the guide 21 formed in the upwardly extending arm 18 of the base 12 and a clamping member 22 pivotally mounted on the slide and having an arcuate head 23 movable toward and from the arcuate

edge face 19 of the base, the slide having an upwardly extending handle 25 and the clamping member 22 also having an upwardly extending handle 24 opposed to the handle 25, the two being arranged as pinch handles, whereby both can be taken hold of at the same time to move the carriage or slide 20 and member 22 vertically along the guide and also move the clamping member 22 on its pivot to release and engage the collar of the shirt being ironed. The clamping member 22 is spring-pressed, and as here shown, the spring 26 is a coiled spring seated in the complementary recesses 27, 28, formed in opposing faces of the carriage and the clamping member 22, the spring 26 having arms 29 and 30 at its opposite ends, the arm 29 being anchored to the carriage at 31 and the arm 30 pressing against the outer face of the clamping member, thus the spring holds the clamping member in position and the clamping member pivots or fulcrums about the spring or about a point above the spring. The clamping means consisting of the head 23 and handles therefor, is thus adjustable upwardly and downwardly along the arm 18 and is also movable on its pivot toward and from the edge face of the base.

30 Additional means, as a screw 32 may be provided for holding the clamping member from displacement.

It will be seen that the operating mechanism is a self-contained structure with the base, which base is attachable to the lower buck of the pressing machine and that the clamping members can be operated directly without the use of complicated and expensive operating mechanism; and further that the operating mechanism extends through the cutout of the upper pressing head of the pressing machine.

This construction provides a particularly simple and efficient way of applying collar band holders to platen type of pressing machines, in which the upper pressing head is carried by the pivoted lever or support. Heretofore, shirt ironing machines have required a different type of pressing machine 60 from the usual pivoted type of garment pressing machine and the operating mechanism for the collar band holder is complicated and expensive.

The base is also provided with suitable expanding members 33, 34 having converging stems 35 movable in suitable guides in the base and operated by means of a slide 36 movable in the guide formed on the boss 16 and connected to the expanding members 33, 34, by rods 38 projecting from the head or block 39 carried by the slide 36. This expanding mechanism forms no part of this invention, except that it is a self-contained structure with the collar band holding means and operating mechanism therefor.

What I claim is:

1. A shirt ironing machine comprising a lower pressing bed or buck, an upper pressing head movable toward and from the bed or buck, the pressing head being formed with a cutout at one end and a collar band holder comprising a base mounted on the upper face of the bed or buck in alinement with the cutout and having an upwardly extending part and clamping means carried by said part and comprising a member coacting with the edge face of the base to hold the collar band, said member including an upwardly extending handle, substantially as and for the purpose set forth. 80

2. A shirt ironing machine comprising a lower pressing bed or buck, an upper pressing head movable toward and from the bed or buck and formed with a cutout in one end, and a collar band holder mounted on one end of the buck in alinement with the cutout and including a base having an upwardly extending arm provided with a handle and a clamping member carried by said arm and movable toward and from the edge face of the base, and having a pinch handle opposed to the former handle, substantially as and for the purpose specified. 85

3. A shirt ironing machine comprising a lower pressing bed or buck, an upper pressing head movable toward and from the buck and formed with a cutout in one end, and a collar band holder including a base mounted on the buck in alinement with the cutout and having an upwardly extending arm, and clamping means carried by the arm and adjustable upwardly and downwardly along the same and also movable relatively thereto toward and from the edge face of the base, substantially as and for the purpose described. 95

4. A shirt ironing machine comprising a lower pressing bed or buck, an upper pressing head movable toward and from the bed or buck, the pressing head having a cutout in one end, and a collar band holder comprising a base mounted on the bed or buck in alinement with the cutout and having an upwardly extending arm, a carriage movable vertically along the arm and a clamping member pivoted to the carriage and movable toward and from the edge face of the base, substantially as and for the purpose specified. 100

5. A shirt ironing machine comprising a lower pressing bed or buck, an upper pressing head movable toward and from the bed or buck and formed with a cutout in one end, and a collar band holder comprising a base mounted on the bed or buck in alinement with the cutout and having an upwardly extending arm formed with a guide, a carriage movable along the guide and provided with an upwardly extending handle, a pivoted spring-pressed clamping member 130

supported by the carriage and having a handle opposed to the former handle and a head movable toward and from the edge face of the base, substantially as and for the purpose set forth.

6. A shirt ironing machine comprising a lower pressing bed or buck, an upper pressing head movable toward and from the bed or buck and formed with a cutout in one end and a collar band holder mounted on the bed or buck in alinement with the cutout and comprising a base mounted on the bed or buck and clamping means comprising a lever having a head movable toward and

from the edge face of the base and an upwardly extending handle, a coiled spring having an arm at one end pressing against the clamping member and an arm at its other end anchored to a part other than the clamping member, the clamping member and said part having the complementary recesses in which the coiled spring is located, substantially as and for the purpose described.

In testimony whereof, I have hereunto signed my name, at Syracuse, in the county of Onondaga, and State of New York, this 30th day of June, 1920.

PHILIP N. BRAUN.
